ATTORNEY

UNITED STATES PATENT OFFICE.

CHARLES TUPPER, OF RIDGELAND, ILLINOIS.

GRAIN-CLEANER.

SPECIFICATION forming part of Letters Patent No. 338,236, dated March 16, 1886.

Application filed September 25, 1885. Serial No. 178,199. (No model.)

To all whom it may concern:

Be it known that I, CHARLES TUPPER, a citizen of the United States, and a resident of Ridgeland, in the county of Cook and State of Illinois, have invented a new and useful Improvement in Grain-Cleaners, of which the following is a specification, reference being had to the accompanying drawings, illustrating the invention, in which—

10 Figure I is a side elevation of my improved grain-cleaner with the side frame-board removed, better to show the internal construction. The external gearing is in its relative position, except where broken away. Fig. II is a view of the front of Fig. I, with some portions broken away. Fig. III is a perspective representation of the grain-stop removed from the cleaner.

15

This invention relates to mills to be set in barns, stables, and other places adjacent to where grain is to be fed, for the purpose of freeing such grain from dust and other impurities; and it consists, in combination with the body, hopper, inclined back board, and blast-fan, of a dust-discharge spout which is placed on the top of the body and above the lower end of the hopper, and an adjustable grain-stop placed through the back board, at or near its junction with the spout, to prevent grain from being driven out by the blast. This construction places the dust-escape adjoining the hopper, and the stop returns any grain which is blown against it. Between the fan and the lower portion of the inclined back board is a deflecting-plate, which prevents any downward blast from the fan. This plate is an elongation of the envelope or case of the fan. The hopper is placed in such position at the top of the fan-case as to bring 20 the falling grain well into the wind before it comes in contact with the back board, so that the dust may all be removed, as hereinafter fully set forth.

25 M represents the back board, which serves as a part of the inclosure to the wind-chamber, and as a conductor for delivering the grain to the receptacle N, and also as a deflector to direct the wind into the dust-spout J, and its lower end serves as a foot to support the bottom of the front portion of the mill.

30 On the top of the body of the mill is placed a dust-spout, J, which in practice should project into some outer apartment or through the wall of a building to the open air, as shown

by the line Q, which represents the line of the 55 building-wall.

The hopper K is set through the spout, as the simplest construction to connect the parts in a substantial cheap manner.

The two sides of the mill are formed of 60 boards A, of the form shown, they being secured to the back M by nails in the ordinary manner, and the front part and bottom of the wind-chamber are formed of thin sheet metal, B C, nailed to the side pieces, A, and the 65 lower end of the metal is turned up at D, to form a deflector for directing the blast upward and preventing it from being driven down on the discharging grain.

At the junction of the back board, M, and 70 spout J is placed a stop, L, which may be adjusted to or from the hopper, as the case may require, to prevent heavy or light grain from being driven up by the blast into the dust-spout.

S is an ordinary slide to regulate the feed 75 of grain to the wind-chamber.

E represents an ordinary fan.

G is a pulley on the fan-shaft, and is driven by a band-wheel, H.

To tighten the band F, the hub d of the 80 wheel-hanger a has extension-wings V, which are slotted to receive screws to hold the gearing to the side of the mill, the slots permitting the hub to be moved from the pulley G, and thus tighten the band. Gear-wheels may 85 be used instead of the band-pulleys.

If desired, the hopper K may connect with the bin of grain above, so that no grain can be used unless it be cleaned.

The back portion of the mill is supported 90 by two legs, P, which come down to a level with the lower end, T, of the back board.

The mill is operated in the usual manner by turning the wheel H by the crank-pin W; but it may be operated by other power.

95 I claim and desire to secure by Letters Patent—

In combination with the body A B C, hopper K, inclined back board, M, and blast-fan E, a dust-discharge spout, J, which is placed on the top of the body and above the lower end of the hopper, and an adjustable grain-stop, L, put through the back board at or near its junction with the dust-discharge spout, as and for the purpose specified.

Witnesses: CHARLES TUPPER.

G. L. CHAPIN,
JAMES ALLEN.
